Assistant Examiner — Amber J Rabie

(74) Attorney, Agent, or Firm — Norton Rose Fulbright
US LLP

(57) CLAIM

The ornamental design for a baby bib, as shown and described.

DESCRIPTION

FIG. 1 is a front elevation view of a baby bib;
FIG. 2 is a rear elevation view thereof;
FIG. 3 is a left side elevation view thereof;
FIG. 4 is a right side elevation view thereof;
FIG. 5 is a top plan view thereof;
FIG. 6 is a bottom plan view thereof;
FIG. 7 is a front isometric perspective view thereof; and,
FIG. 8 is a rear isometric perspective view thereof.
The broken lines shown in the drawings illustrate portions of the baby bid and form no part of the claimed design. Surface shading in the figures is provided solely to indicate contour.

1 Claim, 8 Drawing Sheets
